UNITED STATES PATENT OFFICE.

GIUSEPPE F. PINSUTI, OF NEW YORK, N. Y.

MATCH-RECEPTACLE.

994,784.

Specification of Letters Patent. Patented June 13, 1911.

Application filed August 5, 1910. Serial No. 575,783.

To all whom it may concern:

Be it known that I, GIUSEPPE F. PINSUTI, a citizen of the United States, residing in the borough of Manhattan, city, county, and 5 State of New York, have invented an Improvement in Match-Receptacles, of which the following is a specification.

My present invention relates to a match receptacle and the object thereof is the provision of a receptacle for matches, so constructed that the matches may be normally maintained in an unexposed position and may be brought successively into an exposed position in which position the matches will 15 be available for use as will be hereinafter more particularly described.

In the drawing, Figure 1 is an end view of a receptacle made in accordance with my present invention, the same being shown as 20 adapted to form the outer casing of a cigarette package; Fig. 2 is a cross section on the line y, y , Fig. 1; Fig. 3 is a cross section on line x, x , Fig. 1; Fig. 4 is an elevation of the inner side of the receptacle as shown in Fig. 25 1; Fig. 5 is a perspective view on a reduced scale illustrating the casing shown in Fig. 1; Fig. 6 is a view similar to Fig. 1, showing a modified form of the invention; Fig. 7 is a longitudinal cross section, illustrating the 30 modification of the invention and Fig. 8 is a side elevation and partial cross section, illustrating the inner side of the match receptacle indicated in Fig. 7.

Referring to the drawing and particularly 35 to Figs. 1 to 6, inclusive, in which, I have shown my present invention as applicable to a cigarette package, the casing employed is adapted to the cigarette package from all card-board or any other suitable material 40 and preferably, comprising the side members 10 and the end members 12 and 13, the flap 14 extending from the end member 12, the side member 15, being a continuation of side member 11 and a flap 16 on the long free 45 edge of the member 15, it being understood that these parts are so formed and connected with the surface of the flap 14 against the adjacent surface of the side 11, so as to form a casing for the cigarette package. The 50 side 15 is folded up against the side 11 so as to lie in a position parallel and adjacent thereto and the flap 16 of the side 15 is in-turned and the face thereof is secured to the adjacent portion of the surface of the side 55 11 by a suitable adhesive material or otherwise, so as to form a receptacle for the

matches. The side member 15 is provided with a slot indicated at 17, one end of which is enlarged and approximately centrally in the member 15, there is also a hole or aperture 18. The cigarette packages is indicated at 19 and the cigarettes therein at 20. Between the side members 11 and 15 of the receptacle, I employ a series of matches indicated at 21 and as shown in Figs. 1 and 4, 60 inclusive, these matches 21 may be arranged regularly extending in equal spaced positions from a central hub member 22, the matches and the hub being made of paper or any other suitable material as is customary. 65

I also employ a staple or pivot 23, which is passed through the aperture 18 in the side member 15 and through an aperture provided in the center of the hub 22. The width of the slot 17 is approximately that of 70 the matches 21 and it will now be readily understood that by turning the staple 23, the matches 21 may be moved, so as to cause the same to assume a position in which none of them are exposed at the slot 17 and also that 75 the matches, by turning the staple 23 may be brought successively into position to register with the slot 17, so that by passing the end of the finger through the enlarged end of the slot 17, the end of the match registering with 80 the slot 17, may be turned outwardly, turned off and utilized for lighting a cigarette or any desired purpose. As will be seen by reference to Fig. 6, the said member 15 of the receptacle may be provided with a slot 24, 85 instead of the hole 18 and the matches arranged in a substantially parallel position and connected to a strip 25 instead of to a hub 22. In this instance, the staple 26, passes through the slot 24 through the strip 90 25 and is turned over against the same, so that by shifting the end of the staple, the matches may be moved so as to successively 95 be brought to register with the slot 17.

Referring to Figs. 6 and 7, it will be understood as within the nature and scope of 100 my invention to simply employ a pair of oppositely disposed plates 27 and 28 of any desired material corresponding respectively with the sides 11 and 15 of the receptacle 105 hereinbefore described, these members 27 and 28 being connected by fasteners 29 or otherwise in any desired manner and as will be understood, the receptacle so formed, may be mounted or held and supported in any 110 suitable frame or stand. As shown in Figs. 6 and 7, the member 28 is constructed simi-

larly to the side member 15, as shown in Fig. 6 and the matches employed in this form of the invention being arranged substantially parallel and connected to its strip and secured to and slideable in the frame by means of a staple in all respects similar to that described in connection with Fig. 6.

I claim as my invention:

1. A match receptacle comprising a casing 10 in which there is an opening, a series of matches within the casing and a staple secured to the said series of matches and extending through a wall of the casing and by moving the head of which the series of 15 matches may be moved within the casing to bring the matches successively to the said opening so that each match in turn may be

manually removed from the series of matches at the said opening.

2. A match receptacle comprising a casing 20 having oppositely disposed sides, in one of which there is a slot, a series of matches extending radially from a central member or hub, and a staple passing through the central portion of the said side having a slot therein 25 and through the central portion or hub, from which the said matches extend radially and by which staple the matches may be moved to successively register with the said slot.

Signed by me this 1st day of August, 1910. 30
GIUSEPPE F. PINUTI.
